UNITED STATES PATENT OFFICE

92,944

DESIGN FOR A SOUVENIR MEDAL

Benjamin S. Burrell, East Chicago, Ind.

Application May 19, 1934, Serial No. 51,840

Term of patent 3½ years

To all whom it may concern:

Be it known that I, BENJAMIN S. BURRELL, a citizen of the United States, residing at 3502 Fir Street, East Chicago, in the county of Lake and State of Indiana, have invented a new, original, and ornamental Design for a Souvenir Medal of the 1934 A Century of Progress Exposition, Chicago; of which the following is a specification, reference being had to the accompanying drawing, forming a part thereof.

The design comprises a pictorial group of selected views of the historic progress of the United States, with a blank place for the insertion of the purchaser's autograph and one or more blank places for the reception of photographs as desired, all of which is on one face of the medal which has a marginal rim. The edge of the medal is blank for containing insignia.

I claim:

The ornamental design for a souvenir medal, as shown and described.

BENJAMIN S. BURRELL.
